DESIGN FOR AN ORNAMENTAL COMB OR SIMILAR ARTICLE

Carl Wandt, New York, N. Y.

Application December 15, 1943, Serial No. 112,008

Term of patent 3½ years

(Cl. D86—8)

To all whom it may concern:

Be it known that Carl Wandt, a citizen of the United States of America and a resident of the city of New York, State of New York, has invented a new, original, and ornamental Design for an Ornamental Comb or Similar Article, of which the following is a specification, reference being had to the accompanying drawing, forming part thereof, in which,

Fig. 1 is a front elevational view of an ornamental comb embodying my new design;

Fig. 2 is a rear elevational view thereof; and Fig. 3 is a side elevational view thereof. The characteristic features of the design reside in the ornamentation shown.

I claim:

The ornamental design for an ornamental comb or similar article, substantially as shown and described.

CARL WANDT.
